UNITED STATES PATENT OFFICE.

ROBERT N. CORTHELL, OF AUBURN, MAINE.

SEWING-MACHINE SHUTTLE.

Application filed February 27, 1925. Serial No. 11,985.

To all whom it may concern:

Be it known that I, ROBERT N. CORTHELL, a citizen of the United States, residing at Auburn, in the county of Androscoggin and State of Maine, have invented new and useful Improvements in Sewing-Machine Shuttles, of which the following is a specification.

This invention relates to a shuttle adapted to receive and permit the rotation of a ready-wound bobbin, and provided with a thread-tensioning spring and securing means, fixing the spring to an element of the shuttle in a predetermined position, enabling the spring to tension the thread drawn from the bobbin during the stitch-forming operation of a sewing-machine.

The object of the invention is to provide a shuttle with a tensioning spring, having means for controlling the bobbin by preventing undesirably free rotation thereof.

This object is attained by providing the tensioning spring with a bobbin-controlling spring integral with the tensioning spring, and adapted and arranged to bear yieldingly on an end face of a bobbin in the shuttle, the tensioning spring and controlling spring being applicable as a unit to the shuttle, and each being held by said securing means in position to perform its function, so that the operation of securing a tensioning spring in its operative position, also operatively secures a bobbin-controlling spring, the two springs being adapted to be installed in a shuttle in place of the usual spring adapted only to tension the thread.

Of the accompanying drawings forming a part of this specification,—

Figure 1 is a sectional view, on an enlarged scale, of a shuttle known as the Singer-Central type, provided with a thread-tensioning spring and a bobbin-controlling spring, in accordance with my invention.

Figure 2 is a section on line 2—2 of Figure 1.

Figure 3 is a perspective view, showing only the tensioning spring and the bobbin-controlling spring.

Figure 4 is a side view of the end-thrust supporting member shown by Figure 1.

Figure 5 is a section on line 5—5 of Figure 4.

The same reference characters indicate the same parts in all of the figures.

12 designates a bobbin-thread tensioning spring, adapted to cooperate in the usual manner with a shuttle element 13, here shown as a bobbin case separably engaged by well known means with a shuttle body 14.

The element 13 is provided with the usual or any suitable securing means, for fixing the spring 12 in position to perform its usual thread-tensioning function, the usual means including a tapped orifice 15, in the element 13, and a screw 16, having a shank inserted in an orifice 17 in the spring, and engaging the orifice thread, and a head clamping the spring against the element 13, turning of the spring on the screw being prevented by a tenon 12^a on one end of the spring, engaged with the element 13^a as shown by Figure 2.

The tensioning spring 12 is provided with an integral bobbin-controlling spring 18, adapted and arranged to bear yieldingly on an end face of a bobbin in the shuttle. As here shown, the bobbin is of the ready-wound type including a paper cop tube 19, and a thread winding 120.

The tensioning spring 12 and the bobbin-controlling spring 18 are formed in a single piece from thin resilient sheet metal, such as tempered steel, the tensioning spring being curved, and the controlling spring 18 arranged at an angle to the tensioning spring, so that it is held in position to perform its function by the means securing the tensioning spring to the shuttle.

In the Singer-Central shuttle here shown, the element 13, constituting a bobbin case, is provided with a tubular center post 20, receiving a post 21 on the shuttle body, the bobbin being rotatable on the post 20, as usual. The bobbin-controlling spring 18 extends through an opening 22 in the bobbin case, and is obliquely arranged, as shown by Figure 2, so that it extends well across the bobbin at one side of the center post 20.

The spring 18 is normally held by its resilience in the position shown by dotted lines in Figure 1, and is moved to the full line position, and thus tensioned, by the bobbin. The spring 18, therefore, exerts a retarding pressure on one end face of the bobbin, and presses the opposite end face

against an end-thrust bearing on the shuttle body. Said bearing is preferably a dished disk 23, having a central opening 24, interrupted by slots 25, so that its wall is somewhat resilient. The wall is forced upon the usual enlargement 26, at the base of the post 21.

It will now be seen that the tensioning spring having the bobbin-controlling spring, may be substituted for the ordinary spring not so provided, the shuttle being thus provided with a bobbin-controlling spring performing the function heretofore performed by an independent spring interposed between the head of the bobbin case and the inner end face of the bobbin.

I claim:

A rotary sewing machine shuttle which includes a body having an end thrust bear-

ing, a bobbin case engaged with the body and provided with a center post on which a bobbin inserted in the case is rotatable, the free end of said post being adjacent the thrust bearing on the body, a substantially T-shaped member having its head portion conforming to the curvature of and secured against the outer face of the side wall of the bobbin case, one arm of said head constituting a thread tensioning means, and the stem of said member extending through an opening in the wall of the bobbin case in position to bear on the inner end face of a bobbin therein and press the bobbin against the thrust bearing on the body.

In testimony whereof I have affixed my signature.

ROBERT N. CORTHELL
